UNITED STATES PATENT OFFICE.

CHARLES C. WHITE, OF NEW YORK, N. Y.

SPRING BALANCE.

Application filed December 15, 1923. Serial No. 681,020.

The invention relates to spring balances and more particularly to that type in which a spring operates a drum for taking up a tape or other element.

5 The object of the invention is to provide an improved balance of this type in which provision is made for adjusting the spring tension on the drum; in which the drum can be readily removed from and placed into 10 the carrying case or frame; in which the drum can be inserted endwise into slots in the case and will be held therein by the pawl and ratchet which are provided for 15 adjusting the tension of the spring; in which provision is made for reversing the spindle so that the adjusting means thereon may be 20 rendered accessible from either side of the case to adapt the device for use on the right or left-hand sides of a bed; which is simple 25 in construction, efficient in operation and can be produced at a low cost.

The invention consists in the several novel features hereinafter set forth and more particularly defined by claims at the conclusion 25 hereof.

In the drawings: Fig. 1 is a perspective of a device embodying the invention, the form shown being adapted more particularly as a spring balance for a wall-bed. 30 Fig. 2 is a vertical section. Fig. 3 is a section through the cross-bolt which secures the case and cover together. Fig. 4 is a detail perspective of the body of the case. Fig. 5 is a detail perspective of the cover of 35 the case. Fig. 6 is a perspective of the spindle, around which the drum rotates. Fig. 7 is a section on line 7—7 of Fig. 2.

The invention is exemplified in a spring balance which is designed for wall-beds. A 40 case or frame is provided and this comprises a body formed of a bottom-wall 8 with integral side-walls 9 which may, if desired, be formed of sheet metal and a top wall or cover 10, which is adapted to extend across 45 and fit between the upper margins of side-walls 9. The top 10 is secured to the body by a bolt 11 which extends through holes 12 in sides 9 and ears 13 which extend downwardly from top 10. A spacing sleeve 15 fits between ears 13 and around the shank of bolt 11 to space the sides and prevent the 50 nut on the bolt from buckling top 10. A spacer sleeve 16 is also interposed between the head 15' of the bolt and the outer face of one of the sides 9 to form a free pivot 55 for the pawl 17.

A spindle 20 is removably and rotatably held in the case and is adapted to be inserted in position to retain the drum therein at the inner ends of slots 21, which are formed 60 in sides 9 of the body and are open-ended so that the spindle with the drum thereon may be inserted into the body through one end thereof. Spindle 20 is formed with grooves 23 and 24 into which the edges of 65 the slots 21 fit, so that the spindle will be held against axial movement relatively to the case while it is held in said slots.

The rotatable drum is made up of a pair of disk-like sides 25, each having at its 70 outer margin, an inwardly extending flange 26; and a ring 27 which is held between sides 25 and flanges 26. Each drum-side 25 is also formed with a flange 28 forming a hub which engages and is adapted to rotate 75 around a bushing which comprises a flange 29 rotatably mounted around a shoulder 30 on the spindle 20 and an outwardly extending flange 31 which spaces the drum-side from one of the case-sides 9. Sides 25, with 80 their flanges 26 and 28, are preferably formed of sheet-metal and bushings 31 may be similarly formed. A flat convolute spring 33 has its outer end provided with a hook terminal 34 to engage the edge of a 85 slot 35 in the drum-ring 27 and with a hook 36 at its inner end to fit into either of the longitudinally extending grooves 37, 37' in the spindle 20. A tape 38 or other suitable flexible element is wrapped around and 90 adapted to be taken up by the drum, one end of the tape being fixed to the drum, and the other end is provided with a suitable loop 40 for connection to the bed or other part to be operated thereby. The spindle is held to 95 keep the spring 33 under tension by a ratchet wheel 41 which fits, and is suitably secured on, the square or polygonal end 43 which is integrally formed with the spindle 20, so that the spindle will be rotatable only with 100 the ratchet, and a pawl 17 which engages the ratchet and is pivotally held on the spacer 16 between bolt-head 15' and the case-body. By applying a wrench or suitable key to the square portion 43 of the spindle, 105 the ratchet may be turned to wind up the

spring and increase its tension and the resultant force applied through tape 38 to the bed or other part. By lifting the pawl out of engagement with the ratchet, the spindle 5 will be released for retraction to decrease the tension on spring 33 when that is desired.

In using these balances on wall-beds, it is desirable to apply one to each side of the bed, and in order to have the ratchets where 10 they will be readily accessible at both sides of the bed, and to make the devices applicable with the ratchets accessible disposed, the spindle 20 is reversible in the drum and in the case. To adapt the spindle 15 for connection with the hook-portion 36 of the spring in either of its positions, it is provided with oppositely extending grooves 37 and 37', which are angled relatively to the one another, so that the inner end of the 20 spring can be hooked to the spindle while the latter is in either of its positions. Bolt 11, with its spacer 16, is also reversible, so that the pawl may be positioned adjacent either side of the case. The drum may also 25 be reversed on the spindle wherever that may be necessary to properly position and put the drum under the tension desired for use in different places.

Pawl 17 is positioned so that it will hold 30 the ratchet wheel and spindle at the inner ends of slots 21, so that separate retaining devices are unnecessary, the tension of the tape applied to the drum coacting with the pawl in holding the spindle and drum in 35 operative position.

The invention exemplifies a spring balance, which is readily adjustable so that the tension of the spring-drum may be readily varied as may be necessary. The 40 construction permits endwise insertion of the assembled drum and spindle into operative position in the case. The spindle, drum, ratchet, and pawl are all reversible to adapt the device for use in different locations. The drum is constructed of parts 45 which can be easily assembled to enclose the spring. The case is formed of members which may be formed of sheet metal. The bolt, which provides a pivot for the pawl, 50 serves to secure the top and casing-body together. The device throughout is simple in construction, adapted for use in different places and can be produced at a low cost.

55 The invention is not to be understood as restricted to the details set forth, since these may be modified within the scope of the appended claims, without departing from the spirit and scope of the invention.

60 Having thus described the invention, what I claim as new and desire to secure by Letters Patent, is:

65 1. In a spring balance, the combination of an open-ended case composed of sides and a bottom, the sides having slots therein ex-

tending to one end thereof, a spindle rotatable in said slots, a drum mounted on the spindle, said spindle being removable sideways from said slots with said drum assembled thereon for reversal of its ends in 70 the slots, a spring for operating the drum connected to the spindle, a ratchet reversibly and non-rotatably held on said spindle, and means to hold the ratchet against rotation in one direction when the spindle is 75 in either of its alternative positions.

2. In a spring balance, the combination of an open-ended case composed of sides and a bottom, the sides having slots therein extending to one end thereof, a spindle rotatable in said slots, a drum mounted on the spindle, said spindle being removable sideways from said slots with said drum assembled thereon for reversal of its ends in 80 the slots, a spring for operating the drum connected to the spindle, a ratchet reversibly and non-rotatably held on said spindle, and a pawl adapted to be pivoted to either side of the case so as to hold the ratchet against rotation in one direction when the 85 spindle is in either of its alternative positions.

3. In a spring balance, the combination of a case composed of relatively thin sides and a bottom, said sides having slots therein extending to one end thereof, a drum in said case, a spindle for the drum carried by and rotatable in said slots, said spindle being removable sideways from said slots and provided with annular grooves for receiving the slot-margins, a spring for operating the drum connected to the spindle, and means to hold the spindle against rotation in one direction.

4. In a spring balance, the combination of a case comprising a body having sides and a bottom, and a top extending between the sides and provided with depending lugs, a bolt extending across the body and through said lugs and sides for securing the top to the sides, a spindle removably carried by said sides, a drum mounted on the spindle, a spring for operating the drum connected to the spindle, a ratchet on said spindle, and a pawl pivotally mounted on said bolt for holding said ratchet against rotation in one direction.

5. In a spring balance, the combination of an open-ended case having sides with slots therein, a spindle rotatable in said slots and having annular grooves for receiving the slot-margins, a drum comprising sides, bushings mounted around said spindle between the sides of the body and the drum and provided with inwardly extending annular flanges around which the drum-sides are rotatably mounted, and a spring for operating the drum connected to said spindle.

6. In a spring balance, the combination of an open-ended case composed of sides

and a bottom, the sides having slots therein extending to one end thereof, a spindle rotatable in said slots and removable sidewise therefrom, a drum mounted on the spindle,
5 a ratchet fixed to said spindle, a spring between said drum and said spindle for rotating the drum in one direction, and a pawl

applied to the ratchet to oppose the rotation of the spindle in said direction and to hold the spindle in the slots.

Signed at New York, New York, this 23rd day of July, 1923.
